UNITED STATES PATENT OFFICE.

JOSEF KELLNER, OF BROOKLYN, AND SIDNEY WORMS, OF NEW ROCHELLE, NEW YORK,
ASSIGNORS TO FRANKLIN KNITTING MILLS, OF NEW YORK, N. Y., A CORPORATION
OF NEW YORK.

DESIGN FOR A KNITTED NECKTIE.

43,459.

Specification for Design.

Patented Jan. 21, 1913.

Application filed August 1, 1912. Serial No. 712,786. Term of patent 14 years.

To all whom it may concern:

Be it known that we, JOSEF KELLNER, a subject of the Emperor of Germany, and SIDNEY WORMS, a citizen of the United States, residing, respectively, at Brooklyn, in the county of Kings and State of New York, and New Rochelle, in the county of Westchester and State of New York, have invented a new, original, and ornamental Design for Knitted Neckties, of which the following is a specification, reference being had to the accompanying drawing, forming part thereof.

The drawing is a plan view showing our new design of a knitted tie.

We claim:

The ornamental design for a knitted necktie, as shown.

JOSEF KELLNER.
SIDNEY WORMS.
